UNITED STATES PATENT OFFICE.

WILLIAM R. FOX, OF GRAND RAPIDS, MICHIGAN.

PAPER CLAMP OR GUIDE FOR FRONT-STRIKE TYPE-WRITING MACHINES.

No. 855,509.

Specification of Letters Patent.

Patented June 4, 1907.

Application filed March 16, 1907. Serial No. 362,732.

To all whom it may concern:

Be it known that I, WILLIAM R. FOX, a citizen of the United States, residing at Grand Rapids, in the county of Kent, State of Michigan, have invented certain new and useful Improvements in Paper Clamps or Guides for Front-Strike Type-Writing Machines, of which the following is a specification.

This invention relates to improvements in paper clamps or guides for front-strike typewriters.

The objects of the invention are to provide an improved construction of adjustable clamp or guide for the paper at the front of the platen in close proximity to the printing point, without obstructing the action of the type-bars.

Where light paper is used, a light pressure only is required to hold the same in contact with the platen at the printing point, but, when a stiff card is introduced or when comparatively stiff paper is first introduced, it is frequently desirable to increase the pressure, and I have provided an improved means and devices for accomplishing this result, both as to the method of increasing the tension and the arrangement of the parts.

The objects of my invention are accomplished by the devices and means described in the following specification.

The invention is clearly defined and pointed out in the claims.

A structure embodying the features of my invention is clearly illustrated in the accompanying drawing forming a part of this specification, in which:

Figure 1 is a detail plan view of my improved typewriter paper clamp and guide, in place; Fig. 2 is a detail sectional view on the irregular section, line 2—2 of Fig. 1, and on the line corresponding to line 2—2 of Figs. 3 and 4, showing details of construction; Fig. 3 is an inverted plan view of the front portion of my improved paper guide and clamp; and Fig. 4 is a front elevation of the device; the platen is only indicated in Fig. 2.

In the drawings, similar numerals of reference refer to similar parts throughout the several views.

Referring to the numbered parts of the drawing, a small portion only of the typewriter frame 1 is here illustrated, it being a

cross-bar or portion of the top of the frame. To this is secured the adjustable arm 2 by means of screws 11 in slotted holes therethrough. Ears 8—8 are turned up at each side of the front end of this arm or plate 2, and between the same is pivoted the upwardly extending paper guide 3, made of thin elastic metal as steel, which is slotted at its upper edge at 4, which slot is opposite the printing point of the platen and just beneath the said printing point or one or more spaces removed. The slot 4 is a definite number of scale spaces wide, preferably two. The ends of this are outturned to permit the free passage of the platen 12, with the paper thereon, and so as to pass the usual paper fingers that rest on the platen. The corners at each side of the slot are slightly beveled so that they will not catch the paper fingers in passing by and also to insure free passage of the paper and platen. A finger 5 extends rearwardly from the bottom of this pivoted clamp 3 through an aperture in the front end of the said plate 2 and downwardly and rearwardly, the lower end of the same being turned parallel with the plate 2.

A spring 6 is on the top of the plate 2 and is secured thereto by a suitable rivet 7 and its forward free end rests upon the upper side of the arm 5, holding it normally downward and thereby holding the paper clamp yieldingly in contact with the platen by a gentle pressure, which is sufficient for ordinary purposes. When, however, it is desired to print upon a stiff card, or, for any reason, it is necessary or desirable to exert considerable pressure on the paper against the platen, I provide beneath the plate 2 a swinging arm 9 on pivot 10, the front side of which is beveled to strike over the upper side of the arm 5 and force the same down by a wedging action, thereby forcing the paper clamp or guide 3 against the paper very securely and with sufficient force to cause any card or stiff paper to be clamped properly against the platen at this point. The paper guide or clamp 3 is sufficiently elastic to accommodate the thick card or paper and allow it to pass and at the same time is sufficiently strong to force the same against the platen. The end of this lever is very accessible to the operator; it only needs to be drawn forward to secure this extra clamping effect, and can be immediately

pushed back and release the same when the occasion for extra pressure is passed.

Having thus described my invention, what I claim as new and desire to secure by Letters 5 Patent is:

1. The combination with a typewriter frame, of a forwardly extending plate 2 adjustably secured to the said typewriter frame, the same containing a suitable aperture at 10 the front and provided with ears 8—8 at each side; a paper clamp 3 pivoted to the ears 8—8 and suitably slotted opposite the printing point and having a finger 5 extending through the slot in the plate and beneath the same; a 15 spring 6 on the upper side of the plate 2 and contacting with the upper side of the finger 5 to hold the paper clamp yieldingly in position; and an arm 9 pivoted at 10 to the under side of the plate 2 and beveled to strike above 20 the finger 5 and force the clamp or paper guide firmly into position, co-acting for the purpose specified.

2. The combination with a typewriter frame, of a forwardly extending plate 2 adjustably secured to the said typewriter frame, the same containing a suitable aperture at 25 the front and provided with ears 8—8 at each side; a paper clamp 3 pivoted to the ears 8—8, having a finger 5 extending through the slot in the plate and beneath the same; a 30 spring 6 on the upper side of the plate 2 and contacting with the upper side of the finger 5 to hold the paper clamp yieldingly in position; and an arm 9 pivoted at 10 to the under 35 side of the plate 2 and beveled to strike above the finger 5 and force the clamp or paper guide firmly into position, co-acting for the purpose specified.

3. The combination with a typewriter frame, of a forwardly extending plate 2 secured to the said typewriter frame, provided with ears 8—8 at each side; a paper clamp 3 pivoted to the ears 8—8, having a finger 5; a 40 blade spring 6 on the upper side of the plate 2 and contacting with the upper side of the finger 5 to hold the paper clamp yieldingly in position, for the purpose specified.

4. The combination with a typewriter frame, of a forwardly extending plate 2 secured to the said typewriter frame, provided with ears 8—8 at each side; a paper clamp 3 pivoted to the ears 8—8, having a finger 5; a 45 spring 6 on the upper side of the plate 2 and contacting with the upper side of the finger 5 to hold the paper clamp yieldingly in position; and adjustable means for securing the finger 5 in a fixed relation to the plate 2, for the purpose specified.

5. The combination with the typewriter frame of a forwardly extending plate 2 adjustably secured to the said typewriter frame; a paper clamp 3 pivoted to the forward end thereof and suitably slotted opposite the printing point of the platen and hav-

ing a finger projecting in proximity to the 65 said plate; a spring secured to the said plate and contacting with the said finger to hold the clamp yieldingly in position; and a pivoted arm on the said plate, arranged to swing back of the finger and prevent the action of the spring, thereby affixing the clamp to the plate, co-acting for the purpose specified.

6. The combination with the typewriter frame of a forwardly extending plate 2 secured to the said typewriter frame; a paper clamp 3 pivoted to the forward end thereof and suitably slotted opposite the printing point of the platen, and having a finger projecting in proximity to the said plate; a 70 spring secured to the said plate and contacting with the said finger to hold the clamp yieldingly in position; and a pivoted arm on the said plate, arranged to swing back of the finger and prevent the action of the spring, thereby affixing the clamp to the plate, co- 75 acting for the purpose specified.

7. The combination with the typewriter frame of a forwardly extending plate 2 adjustably secured to the said typewriter frame; a paper clamp 3 pivoted to the forward end thereof and having a finger projecting in proximity to the said plate; a 80 spring secured to the said plate and contacting with the said finger to hold the clamp yieldingly in position; and a pivoted arm on the said plate, arranged to swing back of the finger and prevent the action of the spring, thereby affixing the clamp to the plate, co- 85 acting for the purpose specified.

8. The combination with the typewriter frame of a forwardly extending plate 2 secured to the said typewriter frame; a paper clamp 3 pivoted to the forward end thereof and having a finger projecting in proximity to the said plate; a spring secured to the said 90 plate and contacting with the said finger to hold the clamp yieldingly in position; and a pivoted arm on the said plate, arranged to swing back of the finger and prevent the action of the spring, thereby affixing the clamp to the plate, co- 95 acting for the purpose specified.

9. The combination with the typewriter frame of a forwardly extending plate 2 secured to the said typewriter frame; a paper clamp 3 pivoted to the forward end thereof and having a finger projecting in proximity to the said plate; a 100 spring secured to the said plate and contacting with the said finger to hold the clamp yieldingly in position; and a pivoted arm on the said plate, arranged to swing back of the finger and prevent the action of the spring, thereby affixing the clamp to the plate, co- 105 acting for the purpose specified.

10. The combination with the typewriter frame of a forwardly extending plate 2 secured to the said typewriter frame; a paper clamp 3 pivoted to the forward end thereof and having a finger projecting in proximity to the said plate; a spring secured to the said 110 plate and contacting with the said finger to hold the clamp yieldingly in position; and adjustable means for securing the finger 5 in a fixed relation to the plate 2, co-acting for the purpose specified.

11. The combination with the typewriter frame of a forwardly extending plate 2 secured to the said typewriter frame; a paper clamp 3 pivoted to the forward end thereof and having a finger projecting in proximity to the said plate; a 115 spring secured to the said plate and contacting with the said finger to hold the clamp yieldingly in position; and adjustable means for securing the finger 5 in a fixed relation to the plate 2, co-acting for the purpose specified.

to the said plate; and a blade spring secured to the said plate and contacting with the said finger to hold the clamp yieldingly in position, for the purpose specified.

- 5 11. The combination of a typewriter frame; a forwardly extending support secured to the said frame; a paper clamp 3 of elastic material secured to the forward end of said support; a spring arranged to hold said 10 paper clamp against the platen with slight pressure; and means for connecting said

clamp rigidly to the support, whereby a stronger pressure will be exerted, co-acting for the purpose specified.

In witness whereof, I have hereunto set my 15 hand and seal in the presence of two witnesses.
